UNITED STATES PATENT OFFICE.

ROBERT W. SCOTT, OF BABYLON, NEW YORK, ASSIGNOR TO SCOTT AND WILLIAMS, INC.,
OF NEW YORK, N. Y., A CORPORATION OF MASSACHUSETTS.

MACHINE FOR KNITTING THICKENED-WALE STRUCTURES.

Application filed July 7, 1921. Serial No. 483,037.

This invention relates to machines for knitting fabrics having therein thickened wale structures.

A principal object of the invention is to provide devices capable of attachment to and use in existing knitting machines such as hosiery knitting machines of well known types, (for instances only, of the type illustrated in my Letters Patent No. 1,282,958, 5 October 29, 1918, or of the machines upon which that patent is an improvement, including that shown in my Letters Patent No. 1,148,055 July 27, 1915) and adapted automatically to make in the stockings produced thickened-wale structures of different kinds, and especially adapted to make the fabrics and practice the method disclosed in my copending application Serial 15 No. 483,024 filed of even date herewith 20 Patent No. 1,521,256, dated December 30, 1924.

In the accompanying drawings,

Figure 1 is a development of the cam ring of a knitting machine of one of the types referred to illustrating the relation of the means for forming the thickened-wale structure to the usual knitting instrumentalities;

Figure 2 is a right side elevation of the main frame showing certain control devices hereinafter referred to;

Figure 3 is a plan above the bed plate of the machine, parts being removed;

Figure 4 is a detail section on line 4—4 35 of Fig. 2;

Figure 5 is a detail elevation from the left-hand side of Fig. 3;

Figure 6 is a diagram plan, enlarged, showing the relation of the needles to a cam employed for isolating certain of the needles;

Figure 7 is a similar view showing a different arrangement of needles;

Figure 8 is an elevation comparing different kinds of needles used;

Figure 9 is an explanatory view typical of one species of the fabric; and

Figure 10 is a similar view of another species of the fabric.

Referring now to Fig. 1, I prefer to form the thickened wale structure by engaging the additional yarn *t* fed through a movable yarn guide *t'* from a point stationary during the operation of making the thickened-wale structure and outside of the series 55 of needles *n*. The engagement of the yarn *t* with the needles, and the operation of the yarn guide *t'* may be similar to that explained in my Patent No. 1,256,834. As indicated in Fig. 1, I prefer to effect the selection of needles to engage the yarn *t* by means hereinafter described.

The cam ring 271 carries the usual stitch cams 360, 361, and is provided with some form of top-center cam 357, the leading 65 stitch cam serving as usual to elevate the needles from the height of the ledge 40 at *a*, Fig. 1 to clear their latches, the needles being depressed somewhat by the cam 357 to take their knitting yarn *w* at the main 70 yarn feed *F*, thence being further depressed by cam 360 to knit, and then being advanced to ledge 40, in which position the loop formed at passage of the cam 360 is not cleared below the latches of the needles. 75 Isolation of certain of the needles can now take place for the purpose of wrapping about these needles the yarn *t*. A preferred way of doing this is to move downward into the depression 41 from the ledge 40 all of 80 the needles except the selected and isolated needles left at the level of the ledge 40, which thus encounter the yarn *t*, and upon revolution of the needles in respect to the guide *t'*, form upon themselves a wrapping 85 of the yarn *t*. When the needles rise at *a* the yarn *t* passes below the needle latches, and the wrapping is cast off when the needles bearing it are depressed by the following stitch cam 360. This does not take place 90 until the main yarn *w* has been taken into the hooks of the needles.

By the above arrangements the wrapping of the additional yarn *t* engages the fabric only at the point of passage of the wrapping 95 from the outside to the inside of the group of needles to which it is applied, at which points the yarn *w* overlays the wrap-

ping of the yarn *t*, and hence results in the ends of runs of the yarn *t* being engaged with the yarn *w* and passing about it from the back or rear face of the fabric to the forward face, and then back again. These points of engagement are in the sinker-wale next outside of the group of needles allowed to receive the wrapping of yarn *t*. The runs of the yarn *t* lie wholly on the rear or back face of the fabric, as will be clear from Figs. 9 and 10.

As explained in each of my said Patent No. 1,256,834 and my Patents Nos. 1,267,126 and 1,267,127, May 21, 1918 these thickened wale structures, of whatever nature, and especially when intended as a fashion seam extending down the back of the leg of the stocking, are improved in appearance by intermittent presence of the additional yarn in engagement with the fabric; as explained in the said patents this effect may be secured by depressing all of the needles out of range of the yarn feed *t'* in recurrent courses. This results in a diagonal or lengthwise float of the yarn *t* extending from spot to spot in the fabric made by the engagement of the yarn *t* as explained above. When the fabric is slack or loose, as in the upper part of the leg of a stocking, the floats or runs of the thickening wale yarn (see for instance the runs *y*⁴ Figs. 2 and 4, No. 1,256,834) are not extensible so far as the fabric of the base web. This leads to breakage either of the base web or of these floats.

35 The present mechanism is capable of making a thickened wale structure of intermittent width without floating the yarn *t* from wider spot to wider spot, and may be arranged as desired to perform other variations in the kind of engagement of the yarn *t* with the base web.

Referring now to Fig. 2, in machines of the type illustrated the driving and control mechanism may include a power shaft 30 through which the machine is driven, and a pattern or cam shaft 80 carrying pattern surfaces to determine the orderly operation of the parts. The driving devices may include a shaft 55 actuated from the drive shaft 30 by a pinion on said shaft and a gear 65 rotating at a rate less than the rate of the shaft 30. The rotary element of the knitting head may rotate in unison with its shaft 30 as driven by one of the pulleys 47, the gear 65 rotating at a predetermined ratio with respect to the rate of the knitting head, for instance making one revolution to each four revolutions of the knitting head. The present invention includes means for selecting variable groups of needles at different recurring revolutions of the knitting head (corresponding to courses of the base fabric) and automatic means for selecting first one group and then another or others by 60 means operated from the pattern shaft 80

and from a part rotating in relation to the rotations of the knitting head, preferably the gear 65.

A simple form of these devices may comprise as shown a depressing cam 101, Figs. 1, 3, 5 and 6, mounted on a flat of suitable slope at one end of a lever 420 pivoted for horizontal movement on a standard E, said lever having a depending portion 423 and being held by a tension spring 426 normally to rock upon the pivot E to withdraw the cam 101 away from the surface of the needle cylinder and the butts of the needles. The inner end of the lever 420 may be adjusted to position vertically by a screw 421 and lock nut 422, and the lever may be supported against the reaction of the needle butts by a channel guide 419 suitably fastened on the bed plate D of the machine and engaging the head of screw 421. A stop screw 418 near the end of the lever 420 limits its inward position.

The depending end 423 of the lever 420 carries a follower 424, Figs. 2 and 4, adjustable by set screw 425 and lock nut 426, and adapted when the lever 420 is swung outward from the position shown in Fig. 2 to encounter and be actuated by a segmental cam *b* mounted in a groove on one face of the gear 65, for instance by the screws *b'*. 95 The cam *b* may be of a length to represent any segment of the gear 65; as shown the cam *b* extends through so much of the angle of revolution of the gear 65 as will represent two successive passages of all of the 100 customary set of short butt needles in the machine, i. e., two successive passages of the same arc about 180° of the needle-circle.

The follower 424 may be arched as shown, to enable the recess *k* of the follower to stand over the path of motion of the cam *b* whenever the tip *h* of the follower is permitted to enter the gap between the ends of the arcuate cam *b*. This position of the follower is shown in Fig. 4 and in Fig. 2, 110 and corresponds to the completely withdrawn position 1 of the cam 101, see Fig. 6. In this position the cam 101 is out of contact with needle butts of any length.

The lever 420 is arranged to be moved to 115 place the cam 101 in either of the positions 2 and 3 radially inward of the position 1 by the following means:

The bell crank lever 110 pivoted on the frame of the machine and having one end 120 behind the adjustment screw 427 in portion 423 of the lever 420 rests in its other end upon the periphery of a cam drum 102 fast on the shaft 80, which drum may be that ordinarily relied upon to move the belt 125 shipper 103 for the driving belts for the pulleys 47. The intermediate pulley of these pulleys may be geared to the shaft 30 by gearing, not shown, as usual, so that an intermediate position of the belt shipper 130

results in decreased speed of the machine. The drum 102 effects decrease of speed and stoppage by means of cam 106 having axial projections reacting with a depending lug 104 on the belt shipper 103. In order to relate the motions of the lever 110 to the times of decrease of speed, stoppage and other events controlled by the drum 102, and by other pattern surfaces moved by the shaft 80, cams 107 may be adjustably fastened on the periphery of the drum 102. In the instance shown, a single cam 107 is provided with a low leading end 108; timed to move the lever 110 coincident with entrance of the yarn guide t' , Fig. 1, into operative position; the height of the portion 108 is sufficient to move the lever 420 into contact with the longest butt needles, and is so placed in relation to the teeth of the ratchet, 20 not shown, by which the shaft 80 is moved as to shift the lever 420 and cam 101 forward to move the long butt needles n' during passage of the short butts n^2 , and then to move the long butts; and then to move the 25 cam 101 to the position 2, Fig. 6. This occurs during the passage of the gap between the ends of the cam b on gear 65 at the follower 424, and carries the follower 424 forward into position to engage with the cam 30 ends of the segment b on successive revolutions of the cam b . The cam b moves the follower 424 and the lever 420 to cause the cam 101 to assume the position 3, Fig. 6. Since the cam b occupies something less than 35 half of the periphery of the gear 65, in the instance shown the cam 101 will now remain in position 3 for two revolutions or slightly less and be dropped back to position 2 for two revolutions or slightly more, until the 40 cam 107 has passed from under lever 110.

These motions of the depressing cam 101 are utilized to discriminate between groups of the needles intended to be isolated for the purpose of taking the additional yarn t . 45 In the preferred arrangement, see Fig. 8, the needles n are provided with the usual long butts n' and with the usual short butts n^2 respectively adapted for stocking knitting purposes to be thrown out of action 50 as a whole series and to be operated as an increasing and diminishing series for heel and toe knitting. The needles further include needles of a third length of butt n^3 , and needles of still shorter butts n^4 . The 55 needles having the butts n^3 and n^4 are those adapted to be isolated; a wider group of such needles to receive the yarn t for wider spot may comprise, for instance, needles n^3 and intervening needles n^4 ; a group of 60 needles for a narrower spot may comprise those with the butts n^3 only.

Referring now to Figs. 1 and 6, a single needle with the butt n^4 may be arranged centrally of the usual short butt series n^2 , 65 and this needle n^4 may be flanked by as many

needles with the butts n^3 as desired; one on each side as shown.

When the cam 101 is in the position 3 this cam will engage and depress the needles with the butts n^3 but it will not engage and 70 depress needles with the butts n^4 . When the cam 101 is in the position 2, it will engage and depress the needles n^1 and n^2 but will allow the needle n^3 and the needle n^4 to stand at the full height of the ledge 40 and 75 so isolate them above all the other needles at passage of the guide t' .

The remainder of the operation will now be obvious. When the heel of the stocking is about to be knit the cam 106 will come 80 into operation to move the shipper 103 to decrease the speed of the machine, and during this operation the end 109 of the cam 107 will run off the lever 110, withdrawing the cam 101. This operation is coordinate with withdrawal of the yarn guide t' to cease feeding the yarn t . Re-entrance of the cam 101 is coordinate with the re-entrance of the guide t' ; any suitable automatic means for moving the guide t' into 85 and out of operation may be employed.

Any desired arrangement of the needles having the butts n^3 and n^4 may be made. For instance as shown in Fig. 7 the needles n^3 90 may be an adjacent group and the needles n^4 may be the next needle to one end of this group.

The result of the arrangement shown in Fig. 6 during the withdrawal of the cam 101 to position 3 is to engage the thickening 100 wale yarn t with the sinker wales at each side of a single wale from the needle n^4 , thus making a thin or narrow spot; and when the cam is in position 2 the result is to engage the yarn t with the sinker wales 105 beyond the group of three needle wales knit by the needles n^3 , n^4 , n^3 , as shown in Fig. 10. In the arrangement of Fig. 7 the wide spot is three needle-wales wide, see Fig. 9, but the narrow spot, at needle n^4 , is at one 110 margin of the wide spot. Other arrangements for other patterns of thickening wale yarn inclusion will readily occur to those skilled in the art, and are within my invention.

I claim:

1. A knitting machine having therein main yarn feeding means, and means for placing an additional yarn on certain needles for engagement with the web in 120 such relation as not to be interknitted at wales laterally spaced according to the number of said needles, in combination with means for causing during recurrent courses a lesser number of needles only to receive 125 the additional yarn.

2. A knitting machine adapted for knitting thickening-wale structures having therein a main and an additional yarn guide, and means including a cam movable 130

into operative engagement according to its position with a variable number of a group of needles having different kinds of butts to predetermine the number of needles receiving the additional yarn, in combination with means for moving the cam to engage greater and lesser numbers of the group of needles at recurrent courses.

3. A knitting machine having therein means for feeding a main yarn and an additional yarn for a thickened-wale structure having in combination normal needles, needles differentiated from each other in different degrees adapted respectively to be moved and not to be moved by a cam in different positions, a cam for moving needles to isolate differentiated needles from the other needles, and means for positioning the cam to isolate different groups of the needles during different courses.

4. A knitting machine having therein needles, means for feeding a main yarn to all of the needles, and means for causing groups of needles to receive an additional yarn to make a thickened wale, comprising butts for the thickening-wale needles differentiated from each other and from the remaining needles, in combination with a cam for moving like members of the series of thickening-wale needles only in one position, and means for moving the cam into and out of said position.

5. A knitting machine having a series of needles, means differentiating the needles in respect to their coaction with a cam for the purpose of isolating variable series of needles in accordance with the position of the cam, and a movable cam for this purpose, in combination with means for moving the cam to different positions during knitting of different recurrent groups of courses.

6. A knitting machine having a series of needles, means differentiating the needles in respect to their coaction with a cam for the purpose of isolating variable series of needles in accordance with the position of the cam, and a movable cam for this purpose, in combination with means for moving the cam to different positions during knitting of different recurrent groups of courses comprising a rotary actuating cam, a follower for said actuating cam, a connection therefrom to said needle cam, and pattern controlled means for determining actuation or an idle position for said follower.

7. A knitting machine having therein a series of needles and a movable supplemental needle-cam, the series of needles including groups having butts respectively of different lengths, at least one group including needles adapted to cooperate with said supplemental cam when in one of its positions only, and needles not capable of contact with said cam in any of its positions, in com-

bination with means for holding the supplemental cam in one position during a plurality of courses of knitting, and in another position during an ensuing course or courses.

8. A circular knitting machine having therein a rotary knitting head and needles, and means for isolating different groups of needles according to the different positions of a supplemental cam, in combination with said cam and a movable mounting therefor including a follower adapted to coact with an operating cam carried on a part of the machine rotating at a speed less than that of the knitting head, whereby to retain said cam in said different positions severally during a plurality of courses.

9. A circular knitting machine having therein a rotary knitting head and needles, and means for isolating different groups of needles according to the different positions of a supplemental cam, in combination with said cam and a movable mounting therefor including a follower adapted to coact with the operating cam carried on a part of the machine rotating at a speed less than that of the knitting head, means permitting the follower to reach positions out of contact with the operating cam on either side thereof, corresponding to different positions of the supplemental cam, and pattern operated means for holding the follower on one side of the operating cam and inducing its motion to the other side at predetermined times.

10. In a knitting machine, a rotary knitting head, a supplemental cam and actuating devices therefor comprising a lever having one end near the knitting head and another end near a rotary part of the machine carrying an operating cam and rotating at a different speed from the knitting head, in combination with a fixed needle-depressing cam mounted on one end of the lever and a follower for the operating cam mounted on the other end of the lever.

11. In a knitting machine, a rotary knitting head, a supplemental cam and actuating devices therefor comprising a lever having one end near the knitting head and another end near a rotary part of the machine carrying an operating cam and rotating at a different speed from the knitting head, in combination with a needle cam mounted on one end of the lever, a follower for the operating cam mounted on the other end of the lever, and guide means for the end of the lever carrying the cam adapted to resist flexure of the lever by reaction with the needles.

12. A knitting machine adapted for knitting thickening wale structures having therein a main and an additional yarn guide, a stitch cam and means including a cam movable into operative engagement with a variable number of needles having

different kinds of butts to predetermine the number of needles receiving the additional yarn, said additional yarn guide being positioned to place the yarn on the needles in position to be cast off unknit by the action of the stitch cam, in combination with means for moving the cam operating on the vari-

able number of needles to engage greater and lesser numbers of the needles at recurrent courses.

Signed by me at New York this 6th day of July, 1921.

ROBERT W. SCOTT.
